SPRAYING DEVICE

Nicholas W. De Frees, Hastings, Minn., assignor
to H. D. Hudson Manufacturing Company,
Chicago, Ill., a corporation of Minnesota

Application June 16, 1932, Serial No. 617,570

2 Claims. (Cl. 299—89)

This invention relates generally to improvements in sprayers of the type adapted for spraying insecticides of the type adapted to be carried by the operator, generally by one hand.

One of the general objections to devices of this kind (which include a cylindrical oil tank and a pump having a cylindrical barrel attached directly to the tank in tangential relation thereto) is that the connection is expensive to make, and it is not strong enough to stand the hard and careless usage to which these devices are often submitted. Heretofore, it has been the practice to secure the pump barrel directly to the tank generally by a soldering operation. It has also been the practice to have a depression or opening in the tank to receive the barrel, principally to increase the area of contact for soldering connection. None of such devices have been entirely satisfactory. Moreover, it has been the practice to place the spraying control and mixing valve on top of the barrel in an exposed position where it could come in contact with various obstructions, and in which position it was subject to constant danger of injury.

It is one of the principal objects of this invention to connect the tank and barrel by means lying between them in a protected position, said means having the form of a casting or one-piece body, provided with passages, and to provide means for controlling the passages for obtaining a spraying operation, the entire controlling mechanism being part of, or carried by, or mounted upon this single one-piece connecting member.

Other objects are to provide a simple device with few parts, which parts can be quickly assembled to produce a strong structure; to provide a single casting as a spraying control unit and connector for the pump cylinder and tank; to arrange this casting in a protected position so that its parts will not come in contact with obstructions as when the device is carried or when it is set down; to provide an improved arrangement of the valve for controlling admission of compressed air and fluid and oil, and for mixing and discharging the same; to provide a stop screw adjustment for limiting the opening motion of the valve; to provide means whereby all of the operating parts are carried by a single element which secures the tank and cylinder in operative position; and to arrange the parts so that when the device is in use and when the hand grips the barrel and valve-operating means, the hand is located at the center of gravity of the system, that is the hand lies substantially vertically over the tank when the axis of the

pump barrel is in horizontal position. The structures for obtaining the above objects are features of the invention.

Objects, features and advantages of the invention will also be set forth in the description of the drawings forming a part of this application, and in said drawings

Figure 1 is a side elevation of the sprayer showing the pump cylinder in side view and the tank cylinder in end view, and illustrating the manner of connecting these two elements by a single casting;

Figure 2 is an elevation viewing the end of the cylinder and the side of the tank; and

Figure 3 is an enlarged sectional view taken substantially on line 3—3 of Figure 2.

Numeral 1 indicates the supply tank, and numeral 2 the barrel of an air pump. The long axes of the tank and barrel are arranged substantially perpendicularly to one another and 20 said tank and barrel are connected together by a casting generally indicated 3, which is provided with plate-like members 4—5 having surfaces conforming to the configuration of the outer face of the barrel and tank. The plates are soldered 25 to their respective contacting elements. These plate-like members have comparatively large surface contact and, therefore, a very strong connection is obtained.

The forward portion of the barrel 2 is partitioned as at 10 to provide a terminal compressed air chamber 11. Entrance of air to this chamber under the action of a piston (not shown) is through a passage 12 controlled by check valve 13, and through a second passage 14, in the partition 10. The valve, of course, acts to prevent egress of air after introduction into said terminal chamber. In this instance, the compression chamber lies forwardly of a plane drawn through the long axis of the tank and perpendicularly to the long axis of the barrel. The barrel, however, is not extended forwardly of this line a substantially greater distance than the length of the radius of generation of the cylindrical wall of the tank.

An important feature of the invention relates to the use of a single casting or equivalent integral structure as a means for rigidly connecting the barrel to the tank in operative relation. This casting includes the aforementioned terminal plates 4—5, as well as a tubular casing 25 enlarged at its forward end as at 26 and providing the communicating axially aligned bore portions 27—28. The long axis of this casing is parallel with the long axis of the barrel. The 55

casing is bored as at 29 at the rear, to provide a sliding bearing for a valve stem, and the bore 27 is threaded as at 30.

A capping element and valve seat-forming and valve centering member is generally indicated at 31, and is provided with a reduced portion 32 having threads cooperating with the threads 30 for removably securing the member. The member has a capping portion 33 which cooperates with the end of the casing 26 to close the bore portion 28, a suitable gasket 34 being interposed as shown. The member 31 also has a cylindrical portion 37 of less diameter than the bore 28 which cooperates to form an annular chamber 38 surrounding the portion 31. The valve seat as indicated at 40, is of truncated conical formation, and is convergent toward the spraying orifice 41 of the member 31.

The casting also provides suitable passages for establishing air communication between the compression chamber of the barrel and the bore and tank at one side of the seat 40, and between the tank and the annular chamber 38 on the other side of the seat. These passages are formed by tubular connecting members and traverse the plate-like members. Two of these tubular members 44-45 are provided for establishing compressed air communication between the barrel and tank and may be said to together form a passage which intersects the bore 27. These passages are indicated at 46-47, and lies at one side of the seat 40. The other tubular element 50, establishes communication between the annular chamber and the tank at the opposite side of the valve, through its passage 51.

Suitable passages 52 establish communication between the chamber and the cylindrical bore portion of the plug adjacent the orifice as shown. Cooperative with the seat 40 is a truncated conical valve 55 which has a forward cylindrical extension 56 operative in the cylindrical bore portion 57 of cap 31. The end of this extension acts as a valve for controlling the spraying orifice 41. This extension is of less diameter than the bore portion. Suitable fins 58 are provided on this cylindrical extension which cooperate with the bore 57 to center and guide the valve at a point adjacent the discharge orifice 41. A stem 60 extends rearwardly from the valve 55 and passes through the guide opening 29 in the casting. A suitable expansion spring 61, surrounds the stem 60, and bears against the valve 55 to seat it.

Oil supply tube 62 has one end socketed in the plate 5 and tubular element 50 to establish an oil passage leading from the far periphery of the tank to the chamber 38. Suitable openings 65, 66, 67 are formed in barrel and tank, and are in register respectively with passages 46, 47, 51.

Another feature of the invention relates to the arrangement of the lever 70 for operating the valve 55 and particularly to the location of the pivotal point 71 of the lever and to its being supported on the casting. The pivot 71 for the lever or handle lies substantially on a line A cutting the long axis of the tank and substantially perpendicular to the long axis of the barrel and the handle extends from its pivot rearwardly in direction away from the discharge orifice and longitudinally of and adjacent the barrel. A suitable pivotal connection 72 between an extension 73 of the handle and the valve stem is provided as shown. The lever or handle is arranged adjacent the barrel and movement toward the barrel opens the valve.

Another feature of the invention relates to

the means also carried by the casting for limiting the opening movement of the valve to correspondingly control mixing, and discharge of the mixture. To this end, the casting has a rearward extension 75 which lies rearwardly of the stem beneath the handle adjacent the pivotal point of the handle with the casting, and the set screw 76 has threaded engagement with this extension and is in axial alignment with the stem. It is evident that by adjusting the stop screw the throw of the valve stem in valve opening direction can be controlled.

A combined handle and brace member 77 has the form of the segment of an ellipse and is attached at one end 78 to the pump as by soldering, and is similarly attached by the other end 79 to the tank. The major axis B of the segment is disposed at an angle to the long axis of the barrel as indicated, so that the end portion 80 of the smaller curvature is disposed immediately adjacent the barrel and so that its concave side faces toward the casting, and is also opposed to the end of the control lever. A close placement of this smaller curved end of the ellipse enables the suspension grip to be had which lies near the barrel, and near the center of gravity of the device when the barrel is in the vertical position.

The connector casting 3 is of less width than the diameter of the barrel, and the forward end of the casing 26 is disposed rearwardly of a line C drawn tangent to the tank and touching the end of the barrel.

I claim as my invention:

1. In a spraying device, a cylindrical tank, an air pump including a barrel, the long axis of tank and barrel being substantially at right angles to one another, a casting as the principal means connecting the barrel to the tank, said casting providing suitable intercommunicating passages including a bore having an axis substantially parallel with the barrel axis and having an enlarged terminal portion adjacent one end of the barrel and spaced inwardly from the end of the barrel, a plug detachably secured within the smaller portion of the bore and forming with the larger portion a terminal annular chamber for receiving liquid from the tank, said plug having a discharge orifice axially aligned with the bore, a passage establishing communication between the annular chamber and the discharge orifice, said casting including plate-like members having surfaces conforming to the configuration of the outer faces of the tank and barrel and soldered thereto and also having tubular members which connect the plates with the aforementioned bore, the tank and barrel having openings in register with the bores of said tubular members, and valve means operative in the bore for controlling the passages and discharge orifice for performing a spraying operation, means for operating the valve including a lever pivoted to the casting, said valve having a stem with which the lever engages a stop, said casting having an extension, said extension having a set screw which is adjustable to limit the opening movement of the valve, and said lever lying between the tank and the barrel and opposed to both and extending longitudinally of the barrel and the pivot for the lever lying substantially on a plane cutting the long axis of the tank and perpendicular to the long axis of the barrel, said lever extending in a direction away from the discharge orifice, and a curved handle brace connecting the tank and barrel rear-

wardly of the handle and having a concave portion facing and adjacent the handle.

2. A spraying device comprising a cylindrical tank and an air pump having a barrel, the long axis of the tank and barrel being substantially at right angles to one another, a casting as the principal means connecting the barrel to the tank, said casting having opposed spaced plate-like foot portions respectively conforming to the configuration of and secured to tank and barrel by soldering, said casting having a bore axially parallel with the barrel and terminating in a spraying orifice, a valve seat and valve cooperative with the seat and adapted to control the orifice, passages in said casting and tank and barrel establishing communication between the pump barrel and tank across the bore and at one side of the valve and seat, passages in said casting establishing communication between said tank and bore adjacent said orifice, said casting being of less width than the diameter of the barrel and having its orificed end lying at the inside of a plane tangent to the tank and cutting the end of the 10 barrel, and means for operating the valve. 5

NICHOLAS W. DE FREES.
